UNITED STATES PATENT OFFICE

118,099

DESIGN FOR A BRASSIÈRE

David Blair, Chicago, Ill.

Application October 13, 1939, Serial No. 87,652

Term of patent 7 years

To all whom it may concern:

Be it known that I, David Blair, a citizen of the United States, residing at Chicago, in the county of Cook and State of Illinois, have invented a new, original, and ornamental Design for a Brassière, of which the following is a specification, reference being had to the accompanying drawing, forming part thereof.

Fig. 1 is a perspective view of a brassière showing my new design. The straps are shown broken off.

Fig. 2 is a front elevational view of same with one of the straps shown broken off.

Fig. 3 is a rear elevational view of same with one of the straps shown broken off.

The characteristic feature of my design resides in the combination on the brassière disclosed of the specific breast pockets, as shown.

I claim:

The ornamental design for a brassière as shown and described.

DAVID BLAIR.
